UNITED STATES PATENT OFFICE.

ANTONINO SCATURRO, OF NEW YORK, N. Y.

SAFETY BABY-HAT.

1,104,553.

Specification of Letters Patent. Patented July 21, 1914.

Application filed June 30, 1913. Serial No. 776,725.

To all whom it may concern:

Be it known that I, ANTONINO SCATURRO, M. D., a citizen of the United States, residing at No. 541 Henry street, in the borough 5 of Brooklyn, county of Kings, city and State of New York, have invented a new and useful Safety Baby-Hat to be Used for the Protection of the Child Against Falls.

This invention relates to head gear and 10 particularly to baby hats.

The principal object of the invention is the provision of a simple and efficient device constructed in the form of a mask which may be worn by the infant without affecting 15 capillary respiration and which will protect the child from dangerous accidents resulting from fall.

Further objects of the invention will appear as the following description is read in 20 connection with the accompanying drawing, which forms a part of this application, in which the figure is a perspective view of the cap.

Referring more particularly to the drawings, A represents a crown which may be constructed of any suitable material and which is provided with a band C arranged 25 to fit the head of the child. Connected to the band C and forming an annular ellipsoidal protuberance is a metallic screen B which has secured to its contracted lower 30 end an annular frame piece D to which is secured the usual attaching elastic e.

In practice, the cap is placed upon the head of the infant with the screen B covering 35 the face and back of the head so as to prevent concussions on the head or lacerations of the face for, as it may be seen, the protuberant metallic screen will contact with the ground and perfectly protect the 40 head from engagement therewith, the part A being of sufficient elasticity to absorb the shock the child is relieved of any serious injury.

Claims:

1. In a device of the class described, a crown, a band secured to the lower edge of the crown, a screen wire shield depending from the band and shaped to produce an annular ellipsoidal protuberance, a reinforcing 50 band at the lower end of the shield, and means connected to the lower end of the band for securing the hat to the head of the wearer.

2. A device of the class described comprising a crown, a band secured to the lower portion of the crown, an annular ellipsoidal elastic screen connected to the band, a second band secured to the lower edge of said screen and a chin elastic connected to the 60 lower band.

ANTONINO SCATURRO.
